GAITER

Julius Z. Miller and Lloyd M. Easterling,
Clarksville, Tenn.

Application February 14, 1949, Serial No. 836

Term of patent 7 years

(Cl. D7—7)

To all whom it may concern:

Be it known that we, Julius Z. Miller and Lloyd M. Easterling, citizens of the United States, residing at Clarksville, in the county of Montgomery and State of Tennessee, have invented a new, original, and ornamental Design for a Gaiter, of which the following is a specification, reference being had to the accompanying drawing, forming part thereof.

Figure 1 is a side elevational view of a gaiter showing our new design;

Figure 2 is a front elevational view; and

Figure 3 is a horizontal sectional view taken substantially upon the plane of the section line 3—3 of Figure 1.

We claim:

The ornamental design for a gaiter, as shown.

JULIUS Z. MILLER.
LLOYD M. EASTERLING.
